UNITED STATES PATENT OFFICE.

FREDERICK W. EDWARDY, OF WASHINGTON, DISTRICT OF COLUMBIA.

CONTAINER.

1,401,969.

Specification of Letters Patent.

Patented Jan. 3, 1922.

Application filed October 9, 1916. Serial No. 124,699.

To all whom it may concern:

Be it known that I, FREDERICK W. EDWARDY, a citizen of the United States, and resident of Washington, District of Columbia, have invented certain new and useful Improvements in Containers, of which the following is a specification.

This invention relates to receptacles or containers for parcel post use and especially 10 adapted for the shipment of fragile articles such as eggs.

The objects of the invention are to provide a receptacle which is strong and can be used for an indefinite number of shipments 15 and yet is very light in weight, in other words, a receptacle which is exceedingly and unexpectedly strong for its weight; to make a container of this class which will be practically indestructible, will insulate 20 the articles carried against changes in temperature, will be impervious to grease, is sanitary and washable, will readily permit the insertion and removal of the articles; also to provide a simple and easily manipulated cord means for securing the container 25 closed; a strong but exceedingly light cell structure for receiving eggs; a novel form of tray for carrying the cells; and a means for yieldingly suspending the articles within 30 the container.

Other objects will be apparent from the description taken in connection with the drawings, in which,

Figure 1 is a perspective view of the container showing the means for securing the 35 covers in position;

Figure 2 is a longitudinal section through the same taken on the line 2—2 of figure 3;

Figure 3 is a transverse section taken on 40 the line 3—3 of Figure 2 and illustrating the form and arrangement of the pockets;

Figure 4 is a perspective view of another form of the container and illustrating another arrangement of the means for securing 45 the covers in position;

Figure 5 is a longitudinal section through the form of container shown in Figure 4;

Figure 6 is a perspective view of another form of partition which may be used in the 50 container illustrated in Figures 1 and 2.

The device comprises a cylindrical shell 10, a top cover 11 and a bottom cover 12. These parts are made from sheet material consisting of a vulcanized composition of fiber 55 which is strong, tough, light in weight, washable, a non-conductor of heat and im-

pervious to grease. The covers 11 and 12 may be made by pressing them out from the sheet material and as the material, although very thin and light in weight, is exceedingly strong and rigid, the flange 13 thereof will stand substantially at right angles with the disk portion of the cover, whereby the cover fits very snugly on the shell portion.

As clearly illustrated in Figure 2, means is provided for yieldingly suspending an object in the container whereby the object will not be subjected to shocks and jars which might break the same. As shown, 70 a partition 14 which may be in the form of a tray having the upturned flanges 15, as shown in Figure 2, or in the form of a plain disk 16, as shown in Figure 6, is arranged near and parallel to the bottom cover 12. 75 This partition may be provided with two pairs of diametrically opposite perforations which are adapted to have a cord inserted through the same. Two cords 23, 26 may be used, one for each pair of perforations. As 80 shown at the bottom of Figure 2, one of the cords starting with the knot 17 passes horizontally for substantially 180° around the shell of the container, thence vertically downward as at 18 and under the bottom 85 cover as at 19 and thence vertically upward, as at 20 and through a perforation 21 ar- 90 ranged just above the edge of the flange of the cover and thence downwardly as at 22 and through a perforation 50 of the parti- 95 on and along horizontally under the same as at 23, thence through the diametrically opposite perforation 51 in the partition and upwardly at an angle as at 24 and through a perforation 25 diametrically opposite the 95 perforation 21 in the shell of the container and thence around the shell for substantially 180° to the knot 17. The other cord 26 is arranged in a similar manner. Another partition 27 is arranged near the top cover 100 11 of the container and is yieldingly se- 105 cured in position by two cords 28 and 29 in the same manner as the partition 14. Be- 110 tween the partitions 14 and 27 an object may be interposed. It will be noted that the cord means acting on the two partitions tends to force the same toward each other to clamp the object between the same. More- over, the cord means in addition to suspending the partitions secures the covers in posi- 110 tion.

The container of Figure 2 is illustrated

with two sets of pockets A interposed between the partitions 14 and 27, each set of pockets being separated from the other by means of a partition 30. As shown in Figure 5 3, these pockets are arranged in a circular series and each one is oval shaped to conform as nearly as possible to the contour of an egg. These pockets are made from a strip of flexible but tough sheet material bent to 10 form the same. While a series of six pockets is illustrated, it is obvious that any number might be used. As shown at B, the first and last pockets of the series are telescoped one within the other to thereby hold the series in 15 a circular arrangement. Thus to form a series of six pockets the strip must be long enough and is bent to form seven pockets, the first and seventh pockets being nested or telescoped one within the other. As clearly 20 shown in Figure 3, the large end of each of the pockets is formed with an outwardly projecting transversely extending ridge 31 which spaces the said large end from the flange 15 of the partition and affords a cushion to save the object nested in the pocket from any direct shock in that direction. Of course while the pockets are illustrated as arranged in a partition having a flange 15 or in what may be termed a tray, yet it is 25 30 obvious that this form of pocket has particular utility when arranged in other ways. While two series of pockets A have been illustrated, it is clear that a container may be designed for one series only.

35 The form shown in Figures 4 and 5 comprises a cylindrical shell 10 and covers 11 and 12, the same as in the form shown by Figure 1. The container is adapted to receive one or more sets of pockets which may 40 be of the form illustrated by Figure 3. These pockets may be mounted in trays 32 and 33 and a sheet of corrugated material 34 may be interposed between the series of pockets and the bottom of the tray. At the 45 top of the series of pockets a sheet of corrugated material 35 may be arranged. The covers 11 and 12 are adapted to be secured in position to close the cylindrical container by a single cord means. The arrangement of 50 this cord is very clearly shown in Figures 4 and 5. Starting from the knot 36 just below the top cover the cord extends horizontally around the outside of the shell for substantially 270°, then passes through a perforation 37 in the shell, thence vertically downward as at 38 to enter perforation 39 just above the lower cover, thence downward through this perforation and vertically downward as at 40 and under the bottom 55 cover as at 41, thence vertically upward as at 42 to a perforation 43 arranged diametrically opposite the perforation 39, through this perforation, then vertically upward and outward through a perforation 44 arranged 60 65 diametrically opposite the perforation 37,

then vertically upward as at 45 and over the top of the cover as at 46, then vertically downward on the other side as at 47 and under the first mentioned horizontal portion of the cord adjacent the perforation 37 and 70 thence horizontally around the shell for substantially 90° to the knot 36. In this manner a very simple but exceedingly strong means is provided for securing the covers in position on the shell. By having the knot 75 arranged as described, the section of cord 46 which passes over the top cover is of minimum length between bends and consequently has a very small permissible stretch or extension. This means that the cover will be 80 held in position very securely.

This container is adapted particularly for use in parcel post shipments. The object is to have a container which will not only withstand the rough usage of such shipments but 85 may be repeatedly sent and returned, and carry articles at the minimum cost for postage. The particular material, proportions, and arrangement of parts herein disclosed make a device which is particularly efficient 90 for the purposes desired. The container because of its form is exceedingly strong and yet because of the material used is very light in weight. It is easy to pack and unpack the same and the arrangement of pockets for 95 eggs is not only strong but practically precludes the breakage of the same while being shipped.

Moreover because of the cylindrical form of the container a series of them may be arranged one upon another and inclosed in a sack, and shipped as a single package. Thus the form of the device is particularly adaptable in using the container as a unit for shipments which require a number of containers. 105

It will be noted that because of the sharp turn that the two pieces of cord make as at 37 that a great pressure may be produced to hold the cover, and that this turn holds the cord without letting it slip while the knot is 110 being tied.

Having described the invention what is claimed is:—

1. In combination a cylindrical container, two spaced apart partitions arranged in said 115 container and adapted to have an object interposed between them, and yielding means carried by the container for forcing the partitions toward each other, thereby yieldingly supporting the object in the container. 120

2. In combination a container, a movable partition near one end thereof, said container being formed with oppositely arranged perforations in the shell thereof and further removed from the end than the partition, a partition and perforations similarly arranged at the other end of the container, each partition having cord means passing through the adjacent perforations, whereby the two partitions may be forced 125 130

toward each other to clamp an object therebetween.

3. In combination, a container, two movable spaced apart circular trays therein 5 adapted to receive an object therebetween and yielding means carried by the container for forcing the trays toward each other.

4. In combination a container, means for yieldingly supporting an object therein comprising 10 two spaced apart partitions arranged in the container and flexible means carried by the container connected to the partitions and operable from the exterior of the container for drawing the partitions toward 15 each other.

5. A container comprising in combination a shell member having end covers, partitions

in the container arranged near and parallel to each end and adapted to receive an object therebetween and yielding means for forcing the partitions toward each other and securing the covers in position on the ends of the container. 20

6. A container comprising in combination a shell member having an end cover, a partition in the container arranged near and parallel to the cover and adapted to bear inwardly on the contents of the container and yielding means for forcing said partition inwardly and securing the cover in position 25 on the end of the container. 30

In testimony whereof I affix my signature.

FREDERICK W. EDWARDY.
